UNITED STATES PATENT OFFICE.

GEORGE S. FINNEY, OF CHICAGO, ILLINOIS.

PULVERIZING-MACHINE.

SPECIFICATION forming part of Letters Patent No. 427,228, dated May 6, 1890.

Application filed February 9, 1889. Serial No. 299,277. (No model.)

To all whom it may concern:

Be it known that I, GEORGE S. FINNEY, of Chicago, in the county of Cook and State of Illinois, have invented certain new and useful Improvements in Pulverizing-Machines; and I do hereby declare that the following is a full, clear, and exact description thereof, reference being had to the accompanying drawings, and to the letters of reference marked thereon, which form a part of this specification.

This invention relates to an improvement in pulverizing-machines for reducing dry materials—such as ores, paints, and similar substances—of that class wherein the material being operated upon is introduced into a revolving cylinder within which is located a series of rapidly revolving fans or beaters, and wherein an air-blast is employed to carry away or draw out of the cylinder material reduced to a pulverulent condition by the machine.

The invention consists in the matters hereinafter described, and pointed out in the appended claims.

In the accompanying drawings, illustrating my invention, Figure 1 is a central vertical section of a machine embodying the same. Fig. 2 is a cross-section thereof, taken upon line 2 of Fig. 1. Fig. 3 is a section thereof, taken upon line 33 of Fig. 1. Fig. 4 is a detail section illustrating a modified form of the apparatus.

As illustrated in the said drawings, A is a horizontal frame-base for supporting the several parts of the machine, said base being herein shown as made of timbers connected with each other in rectangular form.

B is a cast-metal frame attached to the base-frame A, and forming the supports or bearings for a revolving cylinder C, which forms the main operative part of the machine. Said cylinder is provided on its opposite sides with two hollow trunnions C' C², by which the cylinder is sustained upon the metal frame B. Said hollow trunnions are made of considerable diameter and constitute the sole inlet and outlet openings of the cylinder, which latter is entirely closed, with the exception of the opposite central openings through the trunnions. The trunnions may rest in ordinary cylindrical bearings within the support-

ing-frame B; but in order to lessen the friction which would otherwise be due to the large diameter of the trunnions I have provided 55 anti-friction roller-bearings, which are constructed as follows:

b b b indicate a plurality of cylindrical rollers disposed around the trunnions between the latter and opposing cylindrical bearing-surfaces B' B' of the frame B.

b' b' are rings located at opposite ends of the rollers b b and provided with bearing-apertures engaging pivot-pins b²b², which pass through said rollers. The said rings b' b' 65 serve to hold the rollers at equal distances apart as the latter are moved forward along the cylindrical bearing-surface B' in the turning of the trunnions in a manner heretofore common and well-known in anti-friction roller-bearings. The upper part of the said cylindrical surface B' is herein shown as formed by a separate cap B², bolted to the main casting B, in the manner clearly shown in Fig. 3.

The trunnion C² at the exit side of the 75 cylinder C is extended considerably outside of or beyond its bearing in the frame B, and is provided with a belt-pulley C³, over which is placed a belt to give rotary motion to the cylinder.

D is a horizontal shaft extending axially through the cylinder C and its hollow trunnions, said shaft being supported at its opposite ends in bearings D' D², which are located at opposite ends of the base-frame A, in the 85 manner illustrated. Said shaft carries inside of the cylinder C a plurality of beaters E, which are rigidly attached to and revolve with the shaft. Said beaters are sustained from the shaft by means of an imperforate disk F, 90 which is affixed to the shaft, and is provided at its outer margin with a series of radial arms or lugs f, to the front faces of which the beaters E are bolted. Said shaft D is provided with a belt-pulley D³, over which is 95 placed a belt for giving motion to the shaft and beaters. The material to be pulverized is fed to the cylinder C through the hollow trunnion C'. For this purpose I have herein shown a hopper G, which is connected with an inclined spout G', which extends into the trunnion and is desirably divided, so as to pass on either side of the shaft D, and provided with a central U-shaped wall g, extend-

ing over the shaft to protect the latter from contact with the material passing through the spout. The said spout G' enters through the upper part of the hollow trunnion, and the 5 lower part thereof is closed by a plate G^2 , containing an opening g' for the inflow of air. The spout G' and plate G^2 will be fitted with moderate closeness to the adjacent margins of the revolving hollow trunnion; but especially-close joints between the parts are not necessary, inasmuch as the admission of a greater or less quantity of air at this point will have no harmful effect.

To the opening through the hollow trunnion 15 C^2 is connected the induction-opening of an air forcing or exhaust device, by which an air-current is drawn through the cylinder for carrying away the pulverized material when the latter reaches a suitable degree of fine- 20 ness. As illustrated in said Figs. 1 and 2, the casing H of a suction-fan surrounds the shaft D adjacent to the end of the trunnion C^2 , and said shaft carries a series of fan-blades $H' H'$, which act within said casing in 25 the manner of an ordinary exhaust-fan. The central opening H^2 of the fan-casing communicates with the hollow trunnion, the parts being provided with surfaces which are in contact with each other or sufficiently close 30 together to prevent any considerable influx of air at the joint between them. The cylinder and its trunnions are revolved at such speed that the material within the cylinder, unless sufficiently light to be carried away by 35 the air-current, is thrown and retained by centrifugal force in the outer part of the cylinder outside of the influence of the air-current. It is not desired, however, that any such material should accumulate in the 40 space between the hollow trunnion C^2 and the shaft D , because such accumulation of material will prevent the free egress of air therethrough. To avoid this result, I place within the hollow trunnion a stationary cylinder H^3 , arranged close to, but preferably 45 not in contact with, the trunnion, said cylinder being attached to a suitable stationary support and connected with the inlet-opening of the fan-casing. The fan-casing is 50 herein shown as located close to the end of the hollow trunnion, and the cylinder H^3 is therefore attached directly to and supported solely by the side wall of the said fan-casing. In order to prevent any fine material from ac- 55 cumulating within the space between the trunnion and shell, there is formed a small hole or series of holes, as indicated at h , Fig. 1, to allow a slight air-current through said space toward the cylinder C , which will prevent the entrance 60 of any material to said space. The fan-casing H is of course connected by a suitable outlet-duct with the place at which the pulverized material that is carried with the air-current through said duct may be deposited.

65 The operation of the apparatus described is as follows: The cylinder C is driven at a relatively high speed—say about three hun-

dred revolutions per minute—the speed of rotation being such that the coarser particles of material introduced into the cylinder will be thrown outwardly and will be held near or remain in contact with the outer peripheral wall of the cylinder during the operation of the machine. The shaft and beaters are driven in a direction opposite to that in which the cylinder is turned and at a very high rate of speed—say one thousand or fifteen hundred revolutions per minute—these revolving beaters operating in connection with the revolving cylinder in the same manner as the beaters of similar machines as heretofore made to break up or pulverize the material fed to the cylinder. The material will be reduced to some extent, as in the case of the larger masses, by direct contact of the beaters therewith; but the material will be pulverized mainly by the production of a rotary air-current within the casing, with which air-currents the larger particles are carried around the casing, and by striking each other and by contact with particles which move with the outer revolving cylinder are by attrition reduced in size and pulverized. The air-current in passing through the cylinder takes from the latter that part of the pulverized material which is sufficiently fine or light to be carried away thereby, while the coarser particles remain in the cylinder and continue to be acted on by attrition until reduced to the desired fineness.

The size of the pulverized material passing from the machine depends upon the speed and revolution in the outer cylinder and the strength of the draft through the same, it being entirely obvious that when the cylinder is run at a high speed the material will be retained therein by centrifugal action for a longer time, and thereby subjected to a greater reduction than when the cylinder is run more slowly. It is also obvious that a strong draft of air through the cylinder would take out more and larger particles, while a weaker draft will only remove the material which has been reduced to a greater extent or to an impalpable powder.

The imperforate disk F , arranged in the manner described, affords an important improvement in machines of the general character herein shown, which is applicable in machines which are otherwise different from that herein illustrated. In similar machines as heretofore constructed the beaters have been placed upon radial arms and the draft of air has passed through the spaces between said arms inside of the beaters. In a construction of this kind the material is found to accumulate behind the beaters by reason of the vacuum there formed, thus preventing the free and continuous passage of material through the machine. In a machine in which the imperforate disk is present, however, the air is deflected outwardly thereby and passes around the edge of the disk at points between the beaters. The air-blast thus passes the

points where otherwise a vacuum would form, thereby effectually preventing the accumulation of any dust or fine particles at the surfaces of the fans. I have herein shown the 5 disk F as arranged to support the beaters E; but an imperforate disk placed between the beaters and the supporting-shaft may be otherwise constructed or arranged, as found convenient or desirable.

10 In Fig. 4 I have shown a somewhat different construction in that part of the machine adjacent to the trunnion C², wherein the cylindric space within the trunnion is filled by a spiral fan placed upon the central shaft 15 and taking the place of the exhaust-fan illustrated in the other figures of the drawings. As shown in said Fig. 4, II are spiral propeller-blades attached to the shaft D and extending from end to end of the hollow trunnion C². J 20 is an air-box having a circular flange j, which is fitted to the end margin of the sleeve C², and J' is an air-outlet pipe attached to said box. In a construction of this kind the fan operating within the hollow trunnion operates to draw the air through the cylinder C 25 and discharge it, together with the pulverized material or dust carried thereby, through the air-pipe J' in the same manner as before described. When the spiral or propeller fan 30 is present, the cylinder H³ (shown in Fig. 1) may be dispensed with, the edges of the fan being brought close to the inner surface of the hollow trunnion, so as to remove any pulverized material or dust that may tend to accumulate thereon.

35 I claim as my invention—

1. A pulverizing-machine comprising a revolving hollow cylinder forming the external casing of the machine, said cylinder being provided with hollow trunnions, a beater-shaft ex-

tending through the hollow trunnions, an imperforate disk mounted upon the shaft, a series of fans or beaters attached to the periphery of said disk, a spout extending through one of the trunnions for the introduction of 45 the material to be operated upon, and an air-exhausting device connected with the other trunnion for producing a forcible air-current through the machine, substantially as described. 50

2. A pulverizing-machine comprising a revolving hollow cylinder forming the external casing of the machine, said cylinder being provided with hollow trunnions, a beater-shaft extending through the hollow trunnions, a series of fans or beaters carried by the shaft, a feed-spout extending through one of the trunnions, a stationary hollow cylinder extending into the other trunnion to a point adjacent to the side wall of the casing, and 55 an air-exhausting device provided with an air duct or passage attached to the outer end of said stationary cylinder, substantially as described.

3. The combination of a revolving cylinder 60 provided with a hollow trunnion for the exit of air and pulverized material, and revolving beaters in said cylinder, an air-exhausting device connected with said hollow trunnion, and a stationary hollow cylinder within the 65 trunnion, said trunnion being provided with one or more small holes h for the admission of air, substantially as described.

In testimony that I claim the foregoing as my invention I affix my signature in presence 70 of two witnesses.

GEORGE S. FINNEY.
